United States Patent Office

Des. 216,576

Patented Feb. 10, 1970

216,576

SEAT FOR TRICYCLE, SIDEWALK BIKE, OR THE LIKE

Loran R. Hill, Olney, Ill., assignor to American Machine
& Foundry Company, a corporation of New Jersey

Filed Jan. 17, 1969, Ser. No. 15,392

Term of patent 14 years

Int. Cl. D12—11, 14

U.S. Cl. D90—16

FIG. 1

FIG. 2

FIG. 3

FIG. 1 is a perspective view of a seat for tricycle, sidewalk bike, or the like embodying my design;

FIG. 2 is another perspective view of the seat; and

FIG. 3 is still another perspective view thereof.

I claim:

The ornamental design for a seat for tricycle, sidewalk bike, or the like, substantially as shown.
